UNITED STATES PATENT OFFICE.

JACOB W. BUTLER, OF BLANEY, SOUTH CAROLINA.

UMBRELLA-SUPPORT.

No. 853,397.

Specification of Letters Patent.

Patented May 14, 1907.

Application filed August 13, 1906. Serial No. 330,317.

To all whom it may concern:

Be it known that I, JACOB W. BUTLER, a citizen of the United States, residing at Blaney, in the county of Kershaw, State of South Carolina, have invented certain new and useful Improvements in Umbrella-Supports; and I do hereby declare the following to be a full, clear, and exact description of the invention, such as will enable others skilled in the art to which it appertains to make and use the same.

This invention has relation to umbrella and parasol supports; and it has for its objects the provision of a device of the kind mentioned that will conveniently support an umbrella on the shoulders and body of a person so that it can be adjusted as desired in respect to position, be held securely in place, and leave the arms free to be employed in doing ordinary work, while the head is protected from the direct rays of the sun.

The invention is embodied in a device comprising a belt provided with a support for the lower end of the umbrella handle, a vertically inclined strap containing a tube for the receipt and support of the umbrella staff, which vertical strap is connected at its lower end and at its upper part at two points, at least, with the belt and breast straps, to which latter are connected shoulder straps that are adapted to receive the arms therethrough and are provided with means for fastening or buckling them on the back or front, according to the manner of wearing the device, an extension of the vertical strap being provided with a button or other suitable means for the fastening of a tape or strap thereto, which latter means is adapted to be wrapped around the braces or umbrella staff or both, the other end of the tape being secured to the buckler means of the shoulder straps or to other suitable parts of the device.

The invention is clearly illustrated in the annexed drawings forming a part of this specification, in which

Figure 1 is a front view of the device showing it as adjusted on the body of a person with the umbrella in front. Fig. 2 is a rear view of the same. Fig. 3 is a sectional view of the vertically inclined strap and tube for supporting the umbrella staff.

Similar figures of reference designate simi-

lar parts or features, as the case may be, wherever they occur.

In the drawings, 10 designates a belt of sufficient width and strength that is adapted to be buckled around the waist of the wearer and is provided with a pad 11 suitably constructed to support the end of the umbrella staff 12, which extends through a tube 13 that is carried by the vertically inclined strap 15. The ball or handle 16 on the lower end of the umbrella staff may be made removable so as to make the staff insertible in its supporting tube.

The upper end of the vertically inclined strap 15 is extended above the tube 13, and the said extension is provided with a button 17, or other suitable means, for fastening the free end of a tape or strap 18 thereto, the other end of which tape is secured to a suitable part of the device and is adapted to be wrapped about the umbrella braces and staff so as to adjust the same in position against one shoulder or the other of the user.

19 and 20 designate the breast straps that are connected at one end with the vertically inclined strap and at the other with the shoulder straps 21 and 22. One of the shoulder straps on each side passes under the arm of the wearer and the other over the shoulder, and at the back each pair of shoulder straps is provided with a buckler strap 23 to buckle the shoulder straps together.

It is to be noted that the strap 15 is so secured in vertically inclined position as to be maintained in that position, and hence keep the tube or socket 13 and the staff of the umbrella in the same position, resulting in maintaining the umbrella in place over the shoulder and the staff to the side of the face of the user.

Limit is claimed for changes in form and arrangement, within the limits of mechanical skill, which do not affect the general nature or spirit of the invention.

What is claimed as the invention, is:—

An umbrella support comprising a waist belt; a pad carried by said belt for supporting the lower end of the umbrella staff; a vertically inclined strap connected at its lower end with said belt, and provided with a tube for the reception of the umbrella staff; shoulder straps adapted to pass under the arms and over the shoulders; a pair of breast

straps disposed upon opposite sides of said inclined strap, each breast strap being connected at one end with said inclined strap at the upper end thereof, and at the other end with the corresponding shoulder strap; and a buckler strap connecting said shoulder straps.

In testimony whereof, I affix my signature in presence of two witnesses.

JACOB W. BUTLER.
